RIBBON OR THE LIKE

Harry Veeder, Great Neck, N. Y.

Application September 19, 1951, Serial No. 247,203

5 Claims. (Cl. 139—420)

1

The present invention relates to a ribbon, or the like; and more particularly to a ribbon of the type especially adapted for use in tying packages, such as gift and holiday packages, and to methods for making the same.

Ribbons of the character described, intended particularly for the tying of gift and holiday packages, are required, by public taste and demand, to be of bright, highly colorful and glittering appearance. To meet such requirements, numerous efforts have been made to incorporate into such ribbons strands of colorful, glittering and light reflecting materials, such as tinsel or colored strips of regenerated cellulose, or the like. The results of all these previous efforts, however, have not been wholly satisfactory because the resulting products generally lacked adequate body, or suppleness and strength, and were fragile and easily spoiled and non-durable. Also, the weaving processes for such ribbons of the prior art was a relatively slow and delicate operation, making production relatively costly, particularly in view of the purpose for which such ribbons were intended.

It is an object of the present invention to provide a ribbon of the character described which incorporates in its structure light reflecting and highly colorful non-fibrous strands and is yet possessed of substantial and adequate body, suppleness and strength for package tying purposes.

It is also an object of the present invention to provide a ribbon of the character described which is of improved strength and durability; is of limited stretchability and of improved shape retaining characteristics.

It is another object of the present invention to provide a ribbon of the character described which is not only bright and glistening in appearance but is also of more colorful and variegated appearance than the ribbons of the same general type heretofore made.

It is a further object of the present invention to provide a ribbon of the character described which may be formed with relative ease and simplicity and at relatively greater speed than ribbons of the same type heretofore made and is, therefore, more economical to produce and to use.

The foregoing and other advantages and superiorities of the ribbons of the present invention will become more readily apparent to those skilled in the art from the embodiment thereof shown in the accompanying drawings and from the description following. It is to be understood, however, that such embodiment is shown by way of illustration only, to make the principles and prac-

2

tice of the invention more readily comprehensible, and without any intent of limiting the invention to the specific details therein shown.

In the drawings:

- 5 Fig. 1 is a fragmentary, plan view of one embodiment of a ribbon of the present invention, partly folded over on itself to show both surfaces thereof, and partly broken away, to show structural details;
- 10 Fig. 2 is an enlarged, more or less diagrammatic sectional view of the same, taken on line 2—2 of Fig. 1, and
- 15 Fig. 3 is a view similar to Fig. 2 of a modified embodiment of a ribbon of the present invention.
- 15 Generally stated, the present invention resides in forming a package tying ribbon with a center portion, running warpwise thereof, which consists of a prewoven textile fabric strip and with marginal portions, likewise running warpwise
- 20 thereof, each of which is formed of one or more highly colorful and/or light reflecting elements or threads, as of tinsel, regenerated cellulose or conventional thread; the center strip and the marginal warp elements being interwoven into a
- 25 unitary ribbon structure by sparsely disposed weft thread or threads.

In a preferred embodiment of the invention the ribbon center strip is formed of cut narrow fabric the edges of which are sealed against fraying and is preferably comprised of a double layer of such cut narrow woven fabric with each of the layer strips differing from the other in appearance, as in color.

Referring more specifically to the accompanying drawings, the embodiment of the ribbon of the present invention therein illustrated comprises a center portion disposed warpwise of the ribbon, generally designated as 10, and consisting of a pair of superposed cut narrow woven fabric strips,

- 30 11 and 12.
- 35 The strips 11 and 12 may be formed of any type of woven fabric suitable for the purpose; woven of either natural or synthetic threads, such as cotton, silk, rayon, nylon, or the like, and may preferably each be of a different color or of otherwise different surface appearance than the other. Thus, for example, the two strips may be of green and red colors, respectively, for Christmas gift package tying. By this arrangement, a single ribbon may present a variegated appearance when it is used in tying a package because of the natural tendency of the ribbon to twist during tying, to expose, alternately the differently appearing surfaces
- 40 55 thereof.

The ribbon centers 11 and 12 may, preferably, for reasons of ease, convenience and speed of production, comprise narrow strips, of desired width, cut from the wide, woven textile fabric in the piece, in a manner well known in the art, by which an entire piece goods width is cut, at one time, into numerous narrow fabric strips. Each strip, 11 and 12, if desired, may have its 5 cut edges sealed against fraying, as by the application of an adhesive, or the like, or by heat, when the nature of the fabric thread permits the use of heat, also in a manner well known in the textile art.

The longitudinal marginal portions of the 15 ribbon of the present invention are each formed of one or more, preferably about four, highly ornamental, preferably colored and light reflecting warp threads or narrow elements, 15, that may each be arranged parallel to an edge of the center strip 10 and to each other and that may blend or contrast with such center strip. Such elements 15 may consist of tinsel threads or of relatively narrow strips of other shiny and light reflecting material, such as 20 colored regenerated cellulose, or of highly colored full threads of conventional type.

The center strip 10 and the warp elements 15 are woven together into unitary ribbon structure by the weft thread or threads, 16, which may be of conventional type and are preferably sparsely spaced across the ribbon.

To eliminate any sharp edges in the ribbon of the present invention due to the character of the material forming the marginal ribbon portion warp elements, to thereby protect the user as well as eliminate any tendency to cut the weft thread 16, the ribbon may also incorporate along each longitudinal edge thereof one or more, as two, additional warp threads, 18, of conventional character, as of cotton, silk, rayon, nylon, or the like, which may be interwoven into the ribbon by the weft 16.

This completes the description of the one embodiment of the ribbon of the present invention. It may here be stated, however, that while the embodiment described is shown to have a center portion 10 consisting of a pair of superposed cut narrow woven fabric strips, the ribbon may also be formed with a center portion of a single layer or ply of woven fabric, preferably cut narrow woven fabric, and having surfaces of different characteristics, as of different colors or different finish, as satin and dull finished surfaces. The center portion 10 may also, if desired, be formed of a conventional, finished-edge ribbon, preferably also with different surface characteristics for its two sides.

In the embodiment illustrated in Fig. 3, the ribbon of the present invention, instead of having a single center portion 10, is shown as formed with a multiple center portions such as 10, each of which may consist of cut narrow woven textile fabric, all of which may be disposed in spaced relation to one another warpwise of the fabric and separated from one another by a group of warp elements, such as 15; all interwoven into unitary ribbon structure by weft thread, such as 16, with the outer edges provided with the edge finishing warp threads such as 18.

In the multiple center portion ribbon described above, each of the center portions may be formed of one ply of cut narrow woven fabric of the like, or of two ply, as illustrated,

and each center portion may have its two surfaces different in appearance from one another as well as from the surfaces of the other of the center portions, in a manner readily understood. In such embodiment of the ribbon of the invention the groups of warp elements of non-woven material may also differ from one another in appearance, as to both color and texture. Such embodiments, therefore, provide a ribbon of maximum colorfulness, brilliance and variegated appearance.

It will be readily apparent that the several embodiments of the invention described above disclose ribbons that are highly colorful, brilliant, and of variegated and attractive appearance, to an extent heretofore not found feasible or possible. It will also be apparent that the ribbons, though formed in the main of cut material, including edges of cut material that is unwoven and sharp-edged, possess, nevertheless, finished woven edges, which will not cut the user's hands and will also prevent the ready tearing of the ribbon across its warp. It will likewise be apparent that in addition to being more impervious to tearing across, the ribbons of the present invention possess all of the body, strength and pliability of a wholly woven ribbon and even in excess of that, conferred thereon by the one or more strips of prewoven fabric incorporated into their structure. It will additionally be apparent that the ribbons of the present invention, because they are formed of strips cut in multiple numbers simultaneously, from wide piece goods, may be made by simple, easy, rapid and economical process and are, therefore, economical to produce and to use.

It will be further apparent that numerous variations and modifications of the ribbons of the present invention and in the methods for making the same may be made by anyone skilled in the art, in accordance with the principles of the invention hereinabove set forth, and without the use of any inventive ingenuity. I desire, therefore, to be protected for any and all such variations and modifications that may be made within the spirit of the present invention and the scope of the claims hereto appended.

What I claim is:

1. A decorative ribbon of the character described, comprising a center, warp-wise extending section consisting of cut, narrow woven textile fabric, said center section having its two surfaces different from one another in appearance, a section formed of at least one relatively narrow, warp element formed of non-woven light-reflecting sheet material along each edge of said center section, and weft thread interweaving said center section with each of said warp elements into unitary structure.

2. A decorative ribbon of the character described, comprising a warp-wise extending center section consisting of a pair of superposed cut narrow woven textile fabric strips, each of said strips differing from the other in color, a section formed of a plurality of relatively narrow, warp elements of non-woven material including at least one element of light reflecting, non-fibrous sheet material along each edge of said center section, and weft thread interweaving said center section with each of said warp elements in unitary structure.

3. A decorative ribbon of the character described, comprising a warp-wise extending center section of cut narrow woven textile fabric, a sec-

tion formed of a plurality of warp elements of relatively narrow, non-woven material, at least one of said warp elements being of light reflecting sheet material, along each edge of said center section, and weft thread interweaving said center section and said warp elements with one another into unitary structure.

4. A decorative ribbon of the character described, comprising a plurality of strips of woven textile fabric arranged warp-wise of the ribbon in laterally spaced relation, a plurality of relatively narrow warp elements of non-woven material at least one of which is of light reflecting material arranged in the space between strips, a plurality of relatively narrow warp elements of non-woven material at least one of which is of light reflecting sheet material along the outer edge of each of the outermost of said strips, and weft thread interweaving each of said strips with each of said warp elements into unitary structure.

5. A decorative ribbon of the character described, comprising a plurality of superposed pairs of strips of woven textile fabric arranged warp-wise of the ribbon in laterally spaced rela-

tion to one another, a plurality of relatively narrow warp elements of light reflecting sheet material arranged in the space between said pairs of strips, a plurality of relatively narrow warp elements of non-woven material at least one of which is of light reflecting sheet material arranged along the outer edge of each of the outermost of said pairs of strips, and weft thread interweaving said pairs of strips with said warp elements into unitary structure.

HARRY VEEDER.
